Patented Dec. 21, 1920.

UNITED STATES PATENT OFFICE.

HENRY KRUESHELD, OF NEW WASHINGTON, OHIO, ASS'GNOR TO THE PERFECTION ELECTRIC PRODUCTS COMPANY, OF NEW WASHINGTON, OHIO.

ELECTRIC HEATER.

1,363,206.

Specification of Letter Patent. Patented Dec. 21, 1920.

Application filed June 25, 1920. Serial No. 391,722.

To all whom it may concern:

Be it known that I, HENRY KRUESHELD, a citizen of the United States, residing at New Washington, in the county of Crawford and State of Ohio, have invented certain new and useful Improvements in Electric Heaters, of which the following is a specification.

This invention relates to electric heaters of that type usually used on tables for toasting or broiling, and has for its object to provide an improved article characterized by simplicity and cheapness with respect to the frame construction and by new and improved means for supporting the heating element in the frame of the device, said heating element comprising a coil of wire which is passed back and forth through insulating supports mounted within the frame, said supports extending upwardly through a reflector plate under which the bases of the supports are clamped. Other improvements will be evident in the details of the device.

The invention may be embodied in various forms, one form being shown in the accompanying drawings in which Figure 1 is a side elevation of the heater. Fig. 2 is a top plan view. Fig. 3 is a section on the line 3-3 of Fig. 2.

Referring specifically to the drawings, 6 indicates a bottom plate having a depending flange 7 around its outer edge, and this is mounted on legs 8 which are secured to the flange 7 at the corners. 9 is a frame made 35 of a single piece or strip of metal the ends of which are butted together at one end of the device as indicated at 10, and this frame is provided at its lower edge with lugs 11 which are fitted through slots in the plate 6 40 and upset thereunder, as shown in Fig. 3.

Fitting within the frame 9 is a reflector plate 12 the upper surface of which is polished, and this plate is provided with a plurality of rows of slots at 13 through which 45 extend upright posts or standards 14 projecting from the bases 15 of the insulating elements. These elements will be made of porcelain or other suitable insulating material, and it will be noted that the bases 15 thereof are confined between the bottom plate 6 and the reflector plate 12, these two plates being fastened together by screws 16 extending through the same. This assembly 50 is very easy to make, and the insulating elements are firmly held in position by the posts 55

extending through the slots 13 and the enlarged bases thereof being confined between the plates, and they do not have to be otherwise attached or secured in place, and furthermore the construction provides an air 60 space 17 between the two plates. The heating element or coil consists of a long wire helix indicated at 18 which is threaded back and forth through holes 19 in the posts 14, down one side of the frame and up the other, 65 the ends being connected to the binding posts 20 to which the conducting cords 21 are connected through an insulating bushing at 22 in the bottom plate 6. Handles 23 may be provided at the ends of the frame, and a 70 grating 24 sets on top of the frame 9 where it is secured by the ears 25.

The main supporting parts of the heater, comprising the plates 6 and 12, the legs 8 and the frame 9, are made of sheet metal, and can be stamped out at small cost. The insulating elements are small and readily molded to shape, and in assembling the parts the frame 9 is readily fixed to the plate 6, and the insulating elements then set in place on the plate 80 and the reflector plate 12 dropped into position and fastened by the screws 16, thus clamping the parts together, after which the heater coil is threaded through the posts and connected to the terminals, ready for use. 85

While I have shown and described this particular construction it is evident that the same is capable of various modifications and I do not wish to limit myself in the construction of the same further than is required by 90 the state of the art or that which comes within the scope of the appended claims.

What I claim is:-

1. An electric heater comprising a stand having a bottom plate, a reflector plate above 95 the same, insulator elements clamped between the plates and having posts projecting through said reflector plate, and a heating element supported by said posts, above the reflector plate.

2. An electric heater having a bottom plate, a reflector plate, insulator elements having bases clamped between said plates and posts projecting through the reflector plate, and a heating element supported by 105 said posts.

3. An electric heater having a bottom plate, a reflector plate, individual insulator elements having bases confined between said plates and posts projecting through the re- 110

reflector plate, said posts having holes through the same, and a heating coil threaded through the openings in the posts.

4. An electric heater comprising a stand 5 having a bottom plate, a frame mounted upon said plate, insulators resting upon said plate and having posts, a reflector plate fitting within the frame and having openings through which the posts project, and a heating element supported by said posts above the reflector plate.

5. An electric heater comprising a stand having a bottom plate, a frame upon said

plate, a slotted reflector plate fitting within said frame, insulators having enlarged bases 15 confined between said plates and upright posts projecting through said slots, fastening means between the plates, to hold the reflector plate and insulators in position, and a heating element supported by said posts. 20

In testimony whereof, I do affix my signature in presence of two witnesses.

HENRY KRUESHELD.
